THERMOSTAT

Filed Nov. 8, 1927

Inventor
Allen A. Dickey

UNITED STATES PATENT OFFICE

ALLEN A. DICKE, OF MONTCLAIR, NEW JERSEY, ASSIGNOR TO PIONEER HEAT REGULATOR COMPANY, A CORPORATION OF NEW JERSEY

THERMOSTAT

Application filed November 8, 1927. Serial No. 231,885.

My invention in its complete embodiment relates to that class of thermostats in which a clock mechanism is employed for the purpose of changing the adjustment of the thermostatic element at a predetermined time. This device is employed frequently in connection with damper controlling mechanism operatively connected with a heating plant or furnace for heating dwellings and other buildings, or with controlling mechanism for valves for heating or cooling systems or in other connections, the movement of the thermostatic element under changes of temperature in the room or other place where the thermostat is situated being caused to control electric circuits by means of which such damper or valve controlling mechanisms are brought into operation, the thermostatic element being adjustable so as to effect the change in its electrical circuits at different degrees of temperature and the clock mechanism being employed to effect desired adjustments of the thermostatic element at predetermined times.

My invention consists in the novel feature hereinafter described reference being had to the accompanying drawing which shows one embodiment of my invention selected by me for purposes of illustration and the said invention is fully disclosed in the following description and claims.

An object of my invention is to simplify and improve the devices heretofore proposed for this purpose and at the same time to cheapen their cost of production. To that end it is proposed to make of one part, preferably a casting, what was formerly made up of many parts, for which purpose the several coacting elements have been so designed and devised as to permit of the use of a single casting to perform multifarious functions.

Further the invention consists in various combinations and constructions, all as hereinafter described and particularly pointed out in the claims.

In the accompanying drawing, forming part of the specification,

Figure 1 is a side elevation, of one illus-

trative form of embodiment of the present invention;

Figure 2 is a front elevation thereof;

Figure 3 is a rear elevation;

Figure 4 is a front view of back plate and the parts mounted thereon; and

Figure 5 is a side view of the parts shown in Figure 4, with the casing shown in medial section.

In said drawing the numeral 11 represents the main frame which is preferably made of a casting of iron or other metal or alloy or any nonmetallic plastic material like bakelite. The upper part thereof projects forwardly to form a mechanism casing and preferably bears on its front face a thermometer 12 having the usual tube and temperature scale as shown. The lower part, preferably of ring form, serves to support the clock in a manner and for a purpose to be set forth later. The thermoresponsive and electrical mechanism is preferably carried by a back plate 13 which may be supported on lugs 14 and 15 being clamped thereto by screws 16.

This back plate carries in electrical contact therewith a post 17 which may be of square cross-section, as shown, which post serves to support a section of bimetallic or other thermoresponsive material 18 which carries a metal finger 19 the lower end of which is located between the two contacts 20 and 21 mounted on posts 22 and 23, respectively, in insulated relation on a lever 24, pivoted at 25 to the back plate 13. The lower part of the lever 24 is arranged in any suitable way to play over a temperature scale as shown.

This may be done by recessing the back surface of the main frame near its lower end as at 26, to provide clearance for the lever 24 and forming the lever with a hook portion ending in the pointer 27. It will be seen that as this pointer is moved over the scale it will move the contacts 20 and 21 in relation to the finger 19. To provide a convenient flexible electrical connection between the movable posts 22 and 23 and the cable leading to the motor, the back plate is preferably provided with two binding posts 28 and 29 mounted on the back plate in insu-

lated relation. These binding posts are connected to the contact supporting posts 22 and 23 by flexible conductors 30. Connected to the binding posts 28 and 29 are the conductors 31 and 32. The outer end of the supporting post 17 is preferably threaded and carries the nut 33, thus forming a third binding post for the conductor 34, the three conductors are preferably formed into a cable 35 which leads to the motor the operations of which are to be controlled.

Due to the arrangement and action of the thermoresponsive element 18, which may be of the usual bimetallic type or its equivalent, the finger 19 moves to the right when the temperature rises and to the left when the temperature drops. When the temperature rises contact is made with contact point 21 thus establishing a circuit through conductors 32 and 34, resulting in the operation of the distant motor to reduce the drafts or to reduce the gaseous, liquid or solid fuel supply. Likewise a drop in the temperature establishes contact between finger 19 and contact 20, providing a circuit through conductors 31 and 34, causing the distant motor to operate to increase the heat supply.

The contact screws may be adjusted by inserting a suitable instrument, as a small screw driver through one of the holes 40 in the sides of the casing. To facilitate this adjustment the casing front is provided with a large opening 41, normally covered by the thermometer. When the latter is removed the contact screws are readily accessible.

The bottom of the casing is partly closed by the wall 42. Circulation of air through the casing and about the element 18 is provided for. It may enter to the rear of the wall 42 and leave through the openings 43 at the top of the casings. Other ventilating openings may be provided for.

The means for adjusting the lever 24 under time control will now be described. For this purpose a suitable clock 50, in this instance a clock of the one day alarm type, is employed. This may be hinged to the main frame as at 51. For this and other purposes there is provided a back plate 52 of generally annular form, secured to the clock by screws 53. This is preferably formed with a right angle extension 54 to which the hinge 51 is attached. The other edge of the plate cooperates with a clasp 55 which holds the clock in the position shown. It may also be provided with a tab cooperating with the recessed lug 56, for accurate alignment of the clock. The back plate is cut away to provide access to the time winding key 57 and to the alarm winding key 58 and the other usual control devices of the clock. Near the key 58 it is cut away in such form as to leave a tab 59 lying in the path of both blades of the key 58, thus serving as a stop to limit the motion of the key, when turned in the

winding direction, at the position shown in dotted lines and, when turned in the opposite direction during the operation of the alarm mechanism in the usual, known way, its motion is stopped in the position shown in full 70

The lever 24 is formed with an extension 24a having a forwardly projecting foot 24b.

In the evening, at about the retiring hour the user swings the clock on its hinge, 75 winds the key 57 and also the key 58 from the full line position to the dotted line position. Either before the clock is returned to normal position or thereafter the lever 24 is moved to the left, (Figs. 2 and 4). The 80 latter action results in the operation of the distant motor to reduce the heat supply.

In the morning, at say 6 o'clock, as shown in Figure 2, the alarm mechanism is released and as a result the key 58 is turned 85 from the dotted line position to the full line position. In so doing it engages the foot 24b and moves the lever 24 toward the left in Figure 3 (to the right as viewed in Figs. 2 and 4) to the central or normal position shown. As the temperature has in most instances dropped below normal during the night the movement to the normal position results in the operation of the motor to increase the heat supply. This results in the 90 raising of the temperature to approximately normal at the rising hour. Furthermore the parts are now adjusted to maintain the desired normal temperature during the entire day.

What I claim is:

1. In a thermostat, a frame, means adapted for attaching the frame to a support, means forming a part of said frame for supporting a clock, said frame being formed with means for supporting a thermoresponsive mechanism and with a mechanism receiving casing, said casing being formed with an opening to permit viewing of and to give access to said mechanism, and a thermometer mounting detachably attached to said casing and serving to cover said opening.

2. In a thermostat, a frame, means adapted for attaching the frame to a support, means forming a part of said frame for supporting a clock, said frame being formed with means for supporting thermoresponsive mechanism, which mechanism comprises opposed contact screws disposed transversely, and with a mechanism receiving casing, said casing being formed with small openings to permit the insertion of a tool to adjust said contact screws.

3. In a thermostat, a frame, means adapted for attaching the frame to a support, means forming a part of said frame for supporting a clock, said frame being formed with means for supporting thermoresponsive mechanism, which mechanism comprises opposed contact screws disposed transverse- 125

ly, and with a mechanism receiving casing, said casing being formed with small openings to permit the insertion of a tool to adjust said contact screws, and being also formed with a large opening to permit viewing of and giving access to the mechanism while it is being adjusted by said tool.

4. In a thermostat, a frame, means adapted for attaching the frame to a support, means forming a part of said frame for supporting a clock, said frame being formed with means for supporting thermoresponsive mechanism, which mechanism comprises opposed contact screws disposed transversely, and with a mechanism receiving casing, said casing being formed with small openings to permit the insertion of a tool to adjust said contact screws, and being also formed with a large opening to permit viewing of and giving access to the mechanism while it is being adjusted by said tool and a thermometer mounting attached to said casing and serving to cover said opening.

CERTIFICATE OF CORRECTION.

Patent No. 1,866,548.

JULY 12, 1932.

ALLEN A. DICKE.

It is hereby certified that the name of the assignee in the above numbered patent was erroneously described and specified as "Pioneer Heat Regulator Company", whereas said name should have been described and specified as Pioneer Heat Regulator Corporation, as shown by the records of assignment in this office; and that the said Letters Patent should be read with this correction therein that the same may conform to the record of the case in the Patent Office.

Signed and sealed this 30th day of August, A. D. 1932.

**M. J. Moore,
Acting Commissioner of Patents.**
